PUSH-BUTTON TYPE PENCIL

Francesco Collura, New York, N. Y.

Application April 16, 1946, Serial No. 662,472

3 Claims. (Cl. 120—17)

1

This invention relates to magazine pencils of the push button type and its object is to make a simpler, more efficient and more durable pencil.

Other objects of the invention will in part be obvious and will in part appear hereinafter.

The invention accordingly comprises an article of manufacture possessing the features, properties, and the relation of elements which will be exemplified in the article hereinafter described, and the scope of the application of which will be indicated in the claims.

For a fuller understanding of the nature and objects of the invention reference should be had to the following detailed description taken in connection with the accompanying drawing, in which:

Fig. 1 is an outline view of the outside of the pencil;

Fig. 2 is a section on the line 2—2 of Fig. 1;

Fig. 3 is section on the line 3—3 of Fig. 1;

Fig. 4 is a section of the lower end of the pencil with certain parts removed;

Fig. 5 is a sectional view of part of the casing showing the feeding jaws and controlling means therefor;

Fig. 6 is a section on the line 6—6 of Fig. 4;

Fig. 7 is a section on the line 7—7 of Fig. 4;

Fig. 8 is a section on the line 8—8 of Fig. 4;

Fig. 9 is a section on the line 9—9 of Fig. 4;

Fig. 10 is a perspective of one of the feed control elements.

The pencil as shown has casing sections A and B of conventional type, one screwed into the lower end of the other. Within the casing section A is a lining sleeve 1 and within the casing section B is a lining sleeve 2 flanged at its upper end at 3 so that it is held between the two sections of the casing and carrying at its lower end a cam ring 4 cooperating with cam surfaces 5 on the outer faces of the lower end of the feed jaws 6.

Mounted loosely within the casing for telescoping action therein is the magazine section 7 carrying at its upper end push button 8 and carrying at its lower end to reciprocate therewith feed jaws 6. Between shoulder 9 on the magazine section 7 and stop member 10 on member 14 a coiled spring 11 is compressed when the push button is forced downwardly and returns the parts to position when pressure on the push button is released. Carried within the magazine section 7 is an inner member 12 having a central bore 13 through which the lead may be fed down into lead tube 14, which extends down through the casing and out of the tip. This lead tube has its sides cut out at 15 so that the feed jaws may

2

grip the lead therethrough. The magazine section 7 and the inner member 12 are connected to move together by forcing in the magazine section as at 16 around a corresponding groove in the member 12. The feeding jaws are connected to the magazine section as best shown in Fig. 6 by turning them in at their upper ends so that they may have as shown, a slight pivotal motion with relation to the magazine section, with which they reciprocate, to permit the lower end of the feeding jaws, where they are roughened at 17 for gripping the lead, to move toward and away from the lead channel.

Side projections 18 on the feed jaws limit the upward motion of the jaws and the magazine under the upward pressure of the spring 11 if there is no lead between the jaws or if for any reason the normal operation of the parts is affected.

20 The means for controlling the movement of the feed jaws in and out with reference to the lead channel may now be described.

Cams 19, projecting laterally from the feed jaws 6, cooperate with corresponding cam surfaces 25 20 carried at the lower end of members 21 one of which is shown in detail in Fig. 10. This member 21 has an arc shaped section at its upper end which wraps around the stop member 10 carried by the lead tube 14 and has a tongue 23 at its 30 upper end which may be bent in against the upper surface of member 10 as shown. One of these members thus fixed in position cooperates with each of the jaw carriers 6.

The position shown in Fig. 2 is the writing position and here feed jaws 6 are shown as clamped against the lead by the cam surface 4 cooperating with the outer cam surface at 5. When it is desired to feed lead through the lower end of the casing, pressure upon the push button carries down the magazine and the jaw carriers. This will carry down the lead with the jaws and the continuation of this movement carries the jaws out from the holding cam ring 4 and at the same time the cams 10 on the jaw carriers pass 40 within the corresponding cam surfaces 20 and continue holding of the jaws against the lead until the parts reach the position shown in Fig. 11. From the position shown in Fig. 11, a slight further movement will carry the cams on the jaw carriers away from the fixed cams 20 and, the pressure upon the push button being relieved, the spring 11 will carry the magazine and jaw carriers on their return movement. On this return movement the cams on the jaw carriers will 50 pass outside the fixed cam 20 as shown in Fig. 12

and the jaws will thus be held free from the lead until the parts have returned to the position shown in Fig. 2 which is the writing position.

Figs. 2, 3, 4, and 9 show means for retaining a light tension upon the lead at all times so that when the grip of the feed jaws is released the lead will not fall down out of the pencil. This means includes a light spring 24 wound around in an external groove 25 toward the lower end of the lead tube 14 and having one end twisted and passing through a radial opening 26 as shown in Figs. 4 and 9 to bear lightly against the lead in the lead tube. The pressure of this spring is such as to hold the lead in place where it is not otherwise held but not such as to interfere with the downward feed of the lead upon the pressure upon the push button.

It will thus be seen that I have shown a mechanism having a comparatively small number of parts in which the feed jaws grip the lead down in and toward the lower end of the tip of the casing so that there is a comparatively short section of lead therebelow, unlikely to break or in any way affect the operation of the pencil and in which the feeding operation in both directions is simple, positive and under firm control.

Since certain changes may be made in the above article and different embodiments of the invention could be made without departing from the scope thereof, it is intended that all matter contained in the above description or shown in the accompanying drawing shall be interpreted as illustrative and not in a limiting sense.

Having described my invention, what I claim as new and desire to secure by Letters Patent is:

1. In a magazine pencil, a casing, a magazine section telescoping therein; jaw members carried with said magazine section and extending to the lower end of the pencil casing, a cam ring fixed within the pencil casing toward the lower end thereof; outer cam faces on said jaw members adapted to cooperate with said cam ring to hold the jaws locked in writing position, a cam projecting from each jaw member; fixed cams mount-

ed within the casing cooperating with said jaw cams to hold the jaws locked against the lead on downward movement of the jaws and free from the lead during the upward movement thereof.

2. In a magazine pencil, a casing, a magazine section telescoping therein, jaw members carried with said magazine section and extending to the lower end of the pencil casing, a cam ring fixed within the pencil casing toward the lower end thereof; outer cam faces on said jaw members adapted to cooperate with said cam ring to hold the jaws locked in writing position, a light spring in the tip of the casing exerting light pressure on the lead, a cam projecting from each jaw member; fixed cams mounted within the casing cooperating with said jaw cams to hold the jaws locked against the lead on downward movement of the jaws and free from the lead during the upward movement thereof.

3. In a magazine pencil, a casing, a magazine section telescoping therein, jaw members carried by pivotal connection with said magazine section and extending to the lower end of the pencil casing, a cam ring fixed within the pencil casing toward the lower end thereof; outer cam faces on said jaw members adapted to cooperate with said cam ring to hold the jaws locked in writing position, a cam projecting from each jaw member; fixed cams mounted within the casing cooperating with said jaw cams to hold the jaws locked against the lead on downward movement of the jaws and free from the lead during the upward movement thereof.

35 FRANCESCO COLLURA.
